United States Patent Office

Des. 177,927
Patented June 5, 1956

177,927

HOSTESS TRAY OR SIMILAR ARTICLE

Norman C. Powers, Cortez, Colo.

Application May 16, 1955, Serial No. 36,004

Term of patent 14 years

(Cl. D44—10)

I claim:

The ornamental design for a hostess tray or similar article, as shown.
